UNITED STATES PATENT OFFICE.

HARRIE ALLEN SACKETT, OF WEST PHILADELPHIA, PENNSYLVANIA, ASSIGNOR TO F. WAYLAND AYER, HENRY N. MCKINNEY, JARVIS A. WOOD, ALBERT G. BRADFORD, AND WILFRED W. FRY, COPARTNERS DOING BUSINESS UNDER THE FIRM NAME OF N. W. AYER & SON, OF PHILADELPHIA, PENNSYLVANIA.

BOX-SUPPORT.

1,159,277.

Specification of Letters Patent.

Patented Nov. 2, 1915.

Application filed March 16, 1915. Serial No. 14,866.

To all whom it may concern:

Be it known that I, HARRIE A. SACKETT, a citizen of the United States, residing at West Philadelphia, in the county of Philadelphia and State of Pennsylvania, have invented 5 certain new and useful Improvements in Box-Supports; and I do hereby declare the following to be a full, clear, and exact description of the invention, such as will enable others skilled in the art to which it 10 pertains to make and use the same.

This invention relates to store furniture, and more especially to stands which are used for the display of merchandise on the counter or on or in the show-case; and one object of the same is to produce a neat and light support of pliable sheet metal which is intended to be furnished and packed with each box or carton of goods, so that the retailer by bending it and applying it as per 15 directions may attach it to the inner end of said box and support the latter in an inclined position with its contents attractively presented to the prospective purchaser.

Another object of the invention is to produce a box support having a display panel capable of being made wider than the box and so formed that the use of the panel is optional with the retailer.

These objects are carried out by constructing and using the support in the manner hereinafter more fully described and claimed, and as shown in the drawings wherein:

Figure 1 is a perspective view of a box 35 taken from the rear end and showing the same held elevated by one of these improved supports, and this view has been made use of to show another support as lying over the front end of the box in the position it assumes when the box reaches the retailer. Fig. 2 is a longitudinal section through the upper end of the box with the support applied. Fig. 3 is a plan view of the blank from which this support is made, the dots 40 indicating the lines on which it is folded. Fig. 4 is a perspective detail of an amplified form of this invention wherein a display panel is added to the support proper, the wings being turned outward at the right side 45 of this view.

Most small commodities are now shipped in quantities packed in a box or carton and suitably wrapped.

It is the purpose of the present invention to supply with each box or carton a little 55 easel or support, the intention being that the retailer will apply the support and attractively display the contents by setting the open box on his counter or show-case.

I have shown the invention as applied to 60 an ordinary pasteboard box measuring perhaps three by six inches, and an inch deep. Let B designate the bottom of this box, E 65 its upper end, S its sides having upper edges U, and C a cover hinged at H to the upper end E if it be hinged, although this cover might be entirely removable.

The blank from which my improved support is made, is best seen in Fig. 3, being cut from thin pliable sheet metal such as tin and at a single descent of the die. The latter may score this blank along the dotted lines in that view to facilitate subsequent bending. I have shown one corner cut off oblique as at 1 excepting for an ear 2 which is left 75 at some point in this oblique line, and I have shown the other corner 3 intact but scored with an oblique line 4 corresponding with the line 1. The blank would not be cut in this way, but I have used this view 80 to show two methods of forming ears at its upper corners, either 2 or 3 which might be employed. The body 5 of the blank between the upright lines 6 and 7 is substantially rectangular and in the present case is substantially 85 square, and said lines define wings 8 and 9 at opposite sides of the body, the upper end of the wings carrying the ears 2 or 3 or in whatever form they are made. These wings in Fig. 3 are shown as substantially 90 rectangular, but in the support shown as applied to the upper end of the box in Figs. 1 and 2 the wings taper downwardly as shown at 8' and 9'. The lower edge of the body is defined by a line 10 beneath which the metal 95 extends a short distance to be turned in between the inturned wings to constitute a foot 11, so that the raw edge of the body will not injure a varnished or highly polished counter or other surface upon which the support 100 finally rests. At two or more suitable points near the top of the body 5 the material thereof is cut through on lines 12 which are herein shown as of inverted U shape to produce tabs 13, and the material may be scored 105 across the line 14 at the foot of these tabs.

Finally the body is preferably provided with two good sized openings or holes 15 and 16.

On the understanding that the upper corners of any one device are alike, it is cut by a die or suitable machine after the manner already described, and folded at right angles on the lines 6, 7 and 10. It is my intention that the width of the body 5 shall be the same as the width of the box or carton, and therefore when folded as just mentioned the support may be slipped over the lower end of the open box after the latter is filled and before its cover is applied, the wings 8 and 9 passing outside the sides S of the box and the foot 11 passing outside its lower end. Each box reaching the retailer has one of the supports within it, as seen at the right in Fig. 1, and it will be obvious that the box cover will pass down outside the wings and foot so that these members hold the support in position during shipment.

In the use of this device as a support, the retailer will open the box by removing or raising its cover C, will take the support out of its position as shown at the right of Fig. 1, will bend down the two tabs 13 on the lines 14 so that they constitute brackets as seen in Fig. 2, and will then pass the upper ends of the wings 8 and 9 outside the upper ends of the two sides S of the box with the supporting brackets 13 under its bottom B at the angle between the latter and its upper end E, bending down the ears 2 or 3 and clamping them over the upper edges U of the sides S so that the distance between the fold line 1 and the upper faces of the brackets 13 is the same as the height of the sides S of the box. In Fig. 2 it will be observed that the width of ear 2 is about half the width of the upper end of the wing 9', or in other words part of said upper end is the fold line 1 which causes the ear 2 to pass over into the box, and the remaining part 1' is behind the box and concealed by its cover C if the box have one. If not, the space 17 forms a convenient receptacle for the insertion of the lower end of an advertising or price card, whose upper portion will obviously rise above the rear and upper end of the box and whose face will be in plain view of the prospective purchaser if there be no cover. The entire device now stands almost wholly behind the box and extends below the same as seen at the left of Fig. 1. It supports and cannot easily be displaced from this end of the box so that the body of the latter is inclined forward, and it is so small that a number of these boxes could be disposed side by side and substantially in contact with each other as in the case of cigar boxes. Assuming that they are displayed within a show-case, the salesman can at any time reach into the back of the same and pass his thumb and fin-

ger through the holes 15 and 16, so that the support becomes a convenient handle by means of which the box can be withdrawn from its place, lifted out of the show-case and placed on the top of the same so that the customer may select his cigar, and then restored to place, without the salesman ever having touched the box at all save perhaps with the tip of his finger where it projects through the hole 15 or 16.

I have shown and described two tabs 13 which are bent down by the retailer into brackets underlying the box as seen in Fig. 2, but obviously there could be a greater or less number than two. I prefer that the ears 2 shall engage the upper edges of the sides S so as not to interfere with the hinge H or the use of the cover C, and also that they shall clamp said edges rather tightly so that the body 5 of the support will stand vertical and be maintained firmly at an acute angle to the bottom B of the box, but this is not absolutely necessary. I prefer to bend inward the foot 11 so as not to scratch a polished counter, but the metal could be beaded or its raw edge otherwise avoided at this point. For hand holds I prefer simply to cut two large holes 15 and 16, but obviously any convenient form of handle might be stamped or cut at this point.

In Fig. 4 is shown an amplification of the same general idea, and I have taken advantage of this view to show a few modifications but these modifications could be used on the simpler type of my invention.

The second object of this invention is described above as contemplating the provision of an advertising panel in conjunction with the box support. This panel is provided by continuing the body 5 upward as shown at 20, and possibly forming wings 28 and 29 on its side edges, the upper ends of the body and wings being given a suitable ornamental configuration as shown. The lower ends of the wings are by preference cut out as shown at 26 and 27 to leave space for the ears 2 which are formed at the upper ends of the main wings 8 and 9, and these cut-outs may also be formed on ornamental lines. The shape of the wings, and in fact even the use of wings 28 and 29, is optional, but if they are employed they will be initially turned down into the plane of the main wings 8 and 9 so that the device can be packed over the body of the box as shown in Fig. 1. In this condition and as seen at the left of Fig. 4 the device reaches the retailer, but he will turn the wings outward, as the wing 29 is shown at the right of this view, so as to increase the width of the panel 20 by the width of both wings 28 and 29. Their faces will be printed, lithographed, or otherwise inscribed with attractive advertising matter, possibly including the price of the commodity contained within the box. Or it

might be possible to make the wings 28 and 29 quite narrow, supply each box with an advertising card, and permit the retailer to lay this card over the panel 20 and bend its wings inward over the edges of the card to clamp the latter in place; and in that case the face of the card will contain advertising matter, and perhaps the back of the card might contain other advertising matter 5 worded a little differently so that the retailer could select which face of the card he would display. This amplification of the idea provides for the use of a display panel or sign holder carried by the upper end of the box 10 support, and yet if the retailer did not wish to employ the same he could bend it back on the line 25 between the panel 20 and body 5, or possibly break it off there. Therefore the use of this amplification is optional.

20 In Fig. 4 a slight modification with respect to the support is shown. Instead of cutting the body 5 on the curved lines 12 and providing it additionally with large holes 15 and 16, I have here cut it with crescent 25 shaped openings 32 and left upstanding tabs 33 at the bottoms of the crescents. When these tabs are bent inward as seen at the right in Fig. 4, they constitute brackets for use in the same manner as illustrated at 13 30 in Fig. 2, but the openings 32 now become in effect large holes through which the fingers may be passed, and therefore the provision of other holes in the body is rendered unnecessary.

35 What I claim is:

1. The combination with a box including a bottom, sides, and ends; of a sheet metal support including a body, wings at the edges thereof standing in parallel planes and spaced sufficiently to pass outside the box-sides, and pliable ears at the upper ends of said wings clamped over the upper edges of the box-sides.
2. The combination with a box including

a bottom, sides, and ends; of a support including a body, wings at the edges thereof bent at right angles to the plane of the body and spaced sufficiently to pass outside the box-sides, pliable elements formed in said body and adapted to be bent under the box-bottom, and pliable elements formed at the upper ends of said wings at points remote from said angles and adapted to be bent over the upper edges of the box-sides where the box is inclined and the body stands vertical. 45

3. The combination with a box including a bottom, sides, and ends; of a sheet metal support comprising an upright body having tabs cut therefrom and adapted to be bent inward to support the box-end, integral 60 right-angular wings at the side edges of the body spaced sufficiently to pass outside the box-sides, ears at their upper ends adapted to be bent inward over the edges of the box-sides; and a display member comprising a 65 panel integral with and of the same width as said body and rising from its upper edge, and initially right-angular wings at the side edges of said panel spaced sufficiently to pass outside the box-sides and cut out at their 70 lower ends over said ears.

4. The herein described box support made of a single piece of sheet metal comprising a rectangular body, upright wings at the edges thereof bent into parallel planes at right 75 angles to that of the body, tabs stamped from the body and adapted to be bent inward between said wings, the upper ends of said wings being formed on oblique lines, and integral ears projecting at points from 80 said lines and adapted to be bent inward over the sides of the box body.

In testimony whereof I affix my signature in presence of two witnesses.

HARRIE ALLEN SACKETT.
